CLAIM

The ornamental design for a gemstone and charm for necklace, as shown and described.

DESCRIPTION

FIG. 1 is a perspective view of a gemstone and charm for necklace showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a front view thereof on a necklace chain.

The broken lines showing a chain necklace in FIG. 8 represent environment and form no part of the claimed design.
